UNITED STATES PATENT OFFICE

RUBEN F. RICHARDS, OF ROBERT LEE, TEXAS.

DESIGN FOR A COTTON-PICKER.

SPECIFICATION forming part of Design No. 31,151, dated July 4, 1899.

Application filed June 9, 1899. Serial No. 719,971. Term of patent 7 years.

To all whom it may concern:

Be it known that I, RUBEN F. RICHARDS, a citizen of the United States, residing at Robert Lee, in the county of Coke and State of Texas, have invented a certain new and useful Design for a Cotton-Picker; and I do declare the following to be a full, clear, and exact description of the invention, such as will enable others skilled in the art to which it applies to make and use the same, reference being had to the accompanying drawings, and to the letters of reference marked thereon, which form a part of this specification.

This invention relates to a new and useful design in cotton-picking devices, and especially to a finger-tip which is adapted to be fitted over the fingers of the operator and having ornamental projections designed for use in picking cotton from the bur of the plant.

My design is clearly illustrated in the accompanying drawings, in which—

Figure 1 is a perspective view of one of my cotton-pickers, and in Fig. 2 I have shown an end view of the device which embodies my design.

The design consists in the two rings A A, which are integral with and at right angles with the solid portion B, connecting the same. The inner circumference of each ring is con-

tinuous with the concaved inner face of the 30 said connecting portion, and extends beyond the rings and is tapered to a point, the latter being inwardly bent as illustrated, while adjacent to the ring beyond which said portion projects, are the two wings B' B', which are 35 V-shaped in cross-section and bent on the arc of a circle corresponding to the curved inner surfaces of the rings, the entire shape of the inner face of said solid portion being such as to snugly fit against the back of the finger of 40 the operator wearing the same, while said wings are disposed in the shape shown so as to partially surround the portion of the finger outside of the rings. The extreme end of said solid portion tapers to a point and is 45 rounded near said point, as shown clearly in the drawings.

What I claim to be new, and desire to secure by Letters Patent, is—

The design for a cotton-picker, substantially as herein described and shown.

In testimony whereof I affix my signature in presence of two witnesses.

RUBEN F. RICHARDS.
